UNITED STATES PATENT OFFICE

2,478,509

CAN OPENER

William L. Stewart, Fitchburg, Mass.

Application February 23, 1946; Serial No. 649,554

3 Claims. (Cl. 30—20)

1

This invention relates to new and useful improvements and structural refinements in can openers and the principal object of the invention is to provide a device of the character herein described, in which a pointed extremity of a stem is adapted to penetrate and engage the center of the end of the can, while a rotatable cutting wheel travels adjacent the marginal bead of the can to separate the end therefrom.

A further object of the invention is to provide a can opener in which said pointed extremity of the stem remains in engagement with the end after the latter has been separated from the can, and the end may thereby be easily and conveniently removed.

Another object of the invention is to provide a can opener which may be readily and conveniently adjusted to accommodate cans of various diameters.

A still further object of the invention is to provide a can opener which is of simple construction and which cannot easily become damaged.

With the above more important objects in view, and such other objects as may become apparent as this specification proceeds, the invention consists essentially of the arrangement and construction of parts as illustrated in the accompanying drawings, in which:

Figure 1 is a side elevation of the invention, showing the same partially broken away and in situ on a can.

Figure 2 is a fragmentary side elevation of a modified embodiment of the invention.

Figure 3 is an end view, taken in the direction of the arrow 3 in Figure 2.

Figure 4 is a fragmentary side elevation, partially broken away, illustrating another modified embodiment of the invention, and

Figure 5 is a cross-sectional view, taken in the plane of the line 5—5 in Figure 4.

Like characters of reference are used to designate like parts in the specification and throughout the several views.

Referring now to the accompanying drawing in detail, the invention consists of a tubular casing 10, defining a handle and formed at one end thereof with a reduced neck 11.

A bevelled cutting wheel 12, provided with a concentric boss 13, is rotatably positioned on the neck 11, being retained thereon by the peened portion 14 of the neck.

A cylindrical extension stem 15 is slidably positioned in the casing 10 and projects at one end therefrom to form the offset portion 16, the same

2

terminating in a pointed extremity 17. The stem 15 is provided with a plurality of spaced, transversely extending apertures 18 and a wing bolt 19, positioned in the side wall of the casing 10, is selectively engageable with any one of said apertures.

When this embodiment of the invention is placed in use, the pointed extremity 17 is caused to penetrate and engage the end 20 of the can 21, substantially at the center of the same. The cutting wheel 12 is then brought into engagement with the end 20 adjacent the marginal bead 22 and by manipulating the casing or handle 10, the wheel 12 will travel around the marginal bead 22 and separate the end 20 from the can 21. After the end has been separated, it may be removed from the can by simply lifting the same with the engaging position 16.

The opener may be adjusted to accommodate cans of various diameters by simply disengaging the wing bolt 19 from one of the apertures 18 and sliding the stem 15 in the casing 10 so that the screw may engage another of said apertures. In this manner, the distance of the wheel 12 from the offset portion 16 may be varied in accordance with the diameter of the can.

It should also be noted that the boss 13 of the wheel 12 is adapted to engage the upper edge of the marginal bead 22, thereby affording substantial support for the wheel while cutting.

Referring now to the modified embodiment of the invention as illustrated in Figures 2 and 3, the same consists of the casing 23, the slidable stem 24, the cutting wheel 25 and the boss 26.

These components are similar to those already described with the exception of the stem 24 which, in this instance, is formed with a longitudinally extending slot 27, in place of the aforementioned apertures 18.

This slot is engaged by a set screw 28 positioned in the side wall of the casing 23, thereby providing releasable means for preventing the rotation and the sliding of the stem in the casing. When it is desired to adjust this opener to various can diameters, the screw 28 is simply loosened and the stem 24 slid in the casing 23. After the desired adjustment has been made, the screw 28 is tightened and the opener is in readiness for use.

With reference now to the final embodiment of the invention as illustrated in Figures 4 and 5, the same consists of the tubular casing 29, the stem 30, the cutting wheel 31 and the boss 32.

These again are similar to their corresponding components already described, the stem 30 also

being provided with the longitudinally extending slot or groove 33, engaged by the set screw 34 in the casing 29.

In this instance, however, the screw 34 does not bear against the stem but simply engages the slot in order to prevent rotation of the stem in the casing. The releasable means for preventing the sliding movement of the stem in this instance, assumes the form of a ratchet tooth rack 35 extending longitudinally at the relatively opposite side of the stem with respect to the slot 33. A coacting lock pin 36 is slidably positioned in the side wall of the casing 29, this pin being formed with one end thereof with the bevelled surface 37, adapted to engage the ratchet teeth of the rack 35.

The pin 36 is normally urged against the rack by means of a resilient strip 38, this being secured at one end thereof to the casing 29 by means of a suitable screw 39. The pin 36 is connected to medially the length of the strip 38 by a rivet 40, and the remaining end of the strip assumes the form of an arcuate finger catch 41.

This embodiment of the invention is adjusted to accommodate various can diameters by simply lifting the finger piece 41 and the associated pin 36 out of engagement with the rack 35 and sliding the stem 30 in the direction of the arrow 42. To slide the same in the opposite direction, the stem is simply pushed to the required amount, while the pin 36 is in engagement with the rack under the resiliency of the strip 38.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

1. A can opener comprising in combination, a tubular casing, a cutting wheel rotatably mounted at one end of said casing, a cylindrical extension stem slidably positioned in said casing and protruding at one end therefrom, an offset portion

at the protruding end of said stem, a pointed extremity on said offset portion, a ratchet tooth rack extending longitudinally on said stem, a coacting pin slidably positioned in the side wall of said casing, said pin being formed with a bevelled surface at one end thereof adapted to engage said rack, resilient means for urging said pin against said rack, and a set screw also positioned in the wall of said casing, said stem being formed with a longitudinally extending slot, and said screw engaging said slot.

2. The device as defined in claim 1, in which said means comprises in combination, a resilient strip secured at one end thereof to said casing, and a finger catch formed at the remaining end of said strip, said pin being secured to medially the length of said strip.

3. A can opener comprising in combination, a tubular handle formed with a diametrically reduced neck at one end thereof, a bevelled cutting wheel rotatable on said neck in axial alignment with said handle, a cylindrical extension stem slidable in said handle and projecting from said neck, an offset portion terminating in a pointed extremity at the projecting end of said stem, a ratchet tooth rack provided medially the length of said stem, a lock pin slidable in the side wall of said handle and adapted for coaction with said rack, a resilient strip secured at one end thereof to said handle and formed with a finger catch at its remaining end, said pin being secured to said strip, said stem being formed with a longitudinally extending groove, and a set screw in said handle slidably engaging said groove.

WILLIAM L. STEWART.
